UNITED STATES PATENT OFFICE

ADAM ROHNER, OF OSHKOSH, WISCONSIN

AUTOGRAPHIC REGISTER

Application filed June 22, 1928. Serial No. 287,410.

This invention relates in general to an autographic register and has more particular reference to the provision of means for insuring the registration of superimposed sheets or strips at the time they are positioned for writing or printing thereon.

One of the principal objects of the present invention is to provide means for insuring the alignment by means of the perforations in a number of sheets in strip form whereby the sheets will be drawn together into accurate register at or near the end of each advancing movement thereof to present them in exact registration at the time of the writing or printing operation thereon.

Among the other objects of the invention are, to provide means for varying the length of feeding action for slips of different lengths; to automatically advance and withdraw the registering means at the end of each feeding movement; to provide means for discharging one or more slips and for retaining one of the slips within the register; to provide a slip cutting shears adjustable from the outside of the register; to provide a box in the register to receive slips cut by the shears; and in general to provide the construction herein shown.

In the accompanying drawings, Figure 1 is a sectional side elevation taken on the line 1—1 of Figure 9, of a register constructed in accordance with the principles of this invention; Figures 2 and 3 are diagrammatic views illustrating the operation of the registration mechanism; Figure 4 is a sectional view taken on the line 4—4 of Figure 9; Figure 5 is a section taken on the line 5—5 of Figure 1; Figure 6 is a sectional view taken on the line 6—6 of Figure 9; Figures 7 and 8 are detail views illustrating different positions of the hook and latch mechanism of Figure 6; Figure 9 is a plan view of a register with parts broken away for clearness; Figure 10 is a perspective illustrating diagrammatically the operation of the registration means; and Figure 11 is a detail view illustrating the variation of the feeding movement cam.

This invention relates to a register for perforated sales slips or tickets which are drawn

from a pack or unwound in multiple from a common roll separated at the writing or printing location by carbon paper which reproduces what is written or printed on the top sheet upon those beneath it. It is desirable to have all of these strips in exact register at the time of writing or printing thereon in order that what is written on the top sheet will be reproduced in the proper location upon the sheets below. In feeding a number 55 of strips of material from the same or separate rolls it is quite difficult to keep the several strips in exact registration because of slippage, different sizes or diameters of the rolls, and the like, and the present invention 60 provides means for engaging and feeding the strips a distance equal substantially to the length of the separate sales tickets and other means for positively engaging in the perforations of the several strips at or near the end 65 of each feeding movement, at the same time releasing the other engaging means and positively drawing the strips forwardly to the end of their feeding movement by the engagement of the perforations thereof. 70

Referring more particularly to the drawings, a casing designated generally by the numeral 12 is provided at one end with an enlargement 13 for receiving a multiple roll 14 of paper or the like consisting of a number 75 of strips 3, 4 and 5 which pass together from the roll along the bottom of the register over a roller or bar 15 and separately over the spacing bars 16 at the top of the register, thence below an autographic opening 17 in 80 the top plate 18.

At one side of the register (see Figure 9) is a casing 19 for holding one or more sheets 20 of carbon paper which are inserted transversely between the strips 3, 4 and 5 below the top 18 so that any writing or printing on the top sheet will be reproduced upon the sheets below. The carbon sheets 20 are removed transversely from the side casing 19 to bring new transferring portions below the 85 opening 17 as required.

The strips pass together between rollers mounted on shafts 21 and 22 each of which has a knurled portion 23 and 24 for engaging and advancing the strips as the rollers are 100

rotated. Below the shaft 22 is a shaft 25 having rollers 26 for engaging the lower strip 5 therebetween and turning it reversely, as clearly shown in Figure 4. The other strips 3 and 4 are deflected upwardly by a top plate 27 extending between the rollers 23 and 24 and extending over the upper shaft 21 is an extension 28 of the top plate 18 which has a sharp tearing edge 29 for engaging the upper strips 3 and 4 as they come from the rollers so that these projecting portions or sales tickets may be easily severed from the remainder of the strips after they are advanced by the feeding rollers.

To actuate the feeding rollers the shafts 21, 22 and 25 are provided at one end with interengaging gears 30 which maintain their interengagement but permit a movement of the shafts 21 and 25 which is opposed by springs 31 bearing directly against them. At the other end one of the shafts 21 has a gear 32 secured thereto which meshes with a larger driving gear 33 mounted on a shaft 34 and having an operating handle 35 secured thereto with a spring pressed handle grip 36 for rotating it. The handle grip has a projection 36^a adapted to yieldingly engage an opening 37^a in a supplementary casing 37 at one side of the register from which it is disengaged after each rotation by an outward pull on the grip.

To release the gripping rollers 23 and 24 from driving engagement with the strips 3, 4 and 5, shaft 21 is raised by a roller 38 mounted at one end thereof which comes into engagement with a cam 39 carried by the driving gear 33 and adjustable in a curved slot 40 of the gear 33 by fastening means 41, the gear itself having an untoothed portion 33^a, as seen more clearly in Figure 11, which forms an extension of the surface of cam 39 when it is desired to vary the length of operating engagement of the gear 33 with its gear 32. When the shaft 21 is raised by the cam 39 and the cam portion 33^a of the driving gear, the shaft 21 will not be rotated, the paper strips between the rollers 23 and 24 will not be advanced, and the variation of these shaft raising members determines the length of feeding movement of the strips 3, 4 and 5, and consequently provides for a variation of the length of the sales slips which are used in the register.

Thus the movement of the rollers 23 and 24 which are pressed toward each other by the shaft engaging springs 31 is interrupted before the end of movement of the driving wheel 33, and the last or aligning movement of the strips 3, 4 and 5 is accomplished in the engagement of spaced aligning perforations 42 in the slips by aligning fingers 43. When these slips are brought up toward the end of their feeding movement by the rollers 23 and 24, the aligning perforations in the several strips may be out of register, as

shown in Figure 2, and the feeding fingers 43 which are held normally in a position below the lowermost strip 5, as shown in Figure 4, are first raised into a position engaging the perforations, as shown in Figure 2, and the fingers are then advanced in engagement with the perforations, as shown in Figure 3, to move the several strips together into alignment, and finally to position the superposed strips in proper register with each other below the opening 17 so that any writing or printing on the uppermost strip will be accurately transferred to the strips below. In this position the preceding upper strips 3 and 4, which are advanced from the register, are positioned so that the inner connected ends are directly below the tearing edge 29 of the cover plate whereby they may be torn manually from their respective strips.

To operate the feeding fingers 43 they are fixed in a transverse shaft 44 which extends through openings 45 in the opposite sides of the register. The shaft is mounted for rocking movement in the upper ends of arms 46, the lower ends of which are secured to a transverse shaft 47 mounted for rotation in the sides of the register and extending beyond the sides thereof. At one end of the shaft 47 is an arm 48 extending at the side of operating gear 38 and having an end contact surface 49 adapted to be engaged by a pin or projection 50 extending laterally from the gear 33 in a position behind or following the cam 39 so that the arm 48 will be engaged by the projection to rock the shafts 46 and 44 when the feeding rollers 23 have been raised from feeding contact with the strips.

At the other end of the rollers 44 and 47 is a controlling mechanism for the feeding fingers covered by a casing extension 51, the details of the mechanism being shown more clearly in Figures 4, 6, 7 and 8. A lever 52 is secured to the shaft 44 having an extension 53 near the shaft 44 arranged to engage a fixed projection 54 extending from the casing 51 (see also Figure 9). The outer or free end of the lever has a projection 55 adapted to engage in a recess 56 of a block 57 secured to the outer side of the casing 12, the movement of the projection 55 into the recess 56 being sufficient to rock the shaft 44 and the feeding fingers 43 upwardly to engage the aligning perforations of the register strips. To control the rocking or feeding movement of the lever 52, an arm 58 is mounted upon a rivet 59 projecting from the wall of the casing 12, the arm having a hook recess 60 near the extremity thereof adapted to engage the end of the lever 52 and its projection 55 and to seat the end of the lever 52 in the recess 60. The arm 58 and the extension 53 of lever 52 are connected by a tension spring 61 and the arm 58 is limited in its movement toward the lever 52 by a projection 62 at the side of the casing 12 so that the

spring 61 tends to force the projection 55 at the end of lever 52 upwardly into engagement with the recess 56 of block 57. The parts are held in their normal position, as shown in Figure 6, by means of a spring 63 connected at one end to the shaft 44, as shown more clearly in Figure 9 and connected at the other end to a cross shaft 64 extending between the sides of the register.

10 The rocking movement of the arms 46 caused by the engagement of the projection 50 of the feeding gear 33 with the cam surface 49 of the arm 48 rocks the lever 52 endwise against the end of the arm 58 until the 15 projection 55 drops into the recess 56, as shown in Figure 7, into which position it is forced by the spring 61. This first advances the aligning and feeding fingers 43, then raises them upwardly, as shown in Figure 2, 20 and the continued rocking movement of the arms 46 advances the feeding fingers in contact with the aligning openings 42 to the position shown in Figure 3 at which time the extension 53 of the lever 52 engages projection 54, thereby rocking the opposite end of the lever 52 oppositely and out of engagement with the recess 56 into a position as indicated in Figure 8, in which the hook recess 60 of the arm 58 will snap over the end of the lever 25 52 and its projection 55 due to the action of the spring 61, thereby rocking the shaft 44 and the feeding fingers 43 downwardly and out of engagement with the aligning openings 42 so that when the contact projection 50 30 slides out of engagement with the arm 48 the controlling lever 52 will be returned to the normal position, as shown in Figure 6, without re-engaging in the recess 56 of the block 57, the returning movement of the arms 46 drawing the extremity of the lever 52 and 35 its projection 55 out of engagement with the hook recess 60, as shown in Figure 8, to the position where it is again ready for operation in contact with block 57, as shown in 40 Figure 6.

45 After the alignment of the strips 3, 4 and 5 they are in position to receive writing or printing and when the lowermost strip is turned reversely between the rollers 26 with 50 in the casing of the register it is supported by a plate 65 which extends horizontally in the register and guides the strip 5 upon a platform 66 carried at the upper end of an inclined box 67 and between upper and lower 55 blades 68 and 69 of a shears for cutting the strip 5 into sales tickets or slips 70 of a pre-determined length, the same as the portions of the strips 3 and 4 which project from the register after each actuation of the handle 60 35, the difference being that the slips 70 are not severed at the same time that the ends of the strips 3 and 4 are torn by contact with with the tearing edge 29. The shear blades 68 and 69 are mounted upon a pivot 71 support- 55 ed by a plate 72 at one side of the machine,

the blades extending through an opening 73, and the position of the shears being adjusted in the opening 73 from the outside of the register by a fastening screw 74. The blades of the shears are inclined and the upper one 68 is fixed in position, and the lower one is made movable to produce the cutting action.

70 To operate the shears an arm 75 is secured to the inner end of the shaft 34 and in the path of the arm as the shaft is rotated is a projection 76 carried at one end of a lever 77 mounted intermediate its ends upon a pivot 78 secured to the side of the register casing 12. At the other end of the lever is a slot 79 for engaging a projection 80 of a vertical slide 81 mounted for movement in straps 82 secured to the side of the casing and carrying a plate 83 at its upper end with a horizontal slot 84 therein adapted to engage the free end of the movable shear blade 69. Engagement 80 of the projection 76 at one end of the lever 77 by the arm 75 depresses this end and raises the other end of the lever against the tension of a spring 85, thereby causing actuation of the shears to cut off that portion of the strip 5 which projects through the shears, as shown in Figure 1. The spring 85 returns the parts to their position, as shown in this figure, as soon as the arm 75 is past the projection 76. The slot 84 is of considerable length to permit the adjustment of the shears in its slot 73 for cutting the slips 70 in various lengths and still maintain the same operating engagement with the movable blade 69.

90 The box 67 is also slidable in the register to be in proper position to receive the slips 70 and it is supported from the sides of the casing by a channel strip 86 which has a fastening screw 87 for adjusting it in the slot 88 at the side of the casing, the box 67 being held in inclined position, as shown in Figure 1, to collect the sales slips 70 in compact form. A lid 89 extends upwardly from the end of the box to prevent the strip 5 and the slips 70 from passing beyond or without the box 67 and for directing them within the box.

100 A sufficient space is left between the lower end of the box 67 and the channel support 86 to allow the strips 3, 4 and 5 to pass thereunder on their way from the roll 14 to the roller 15. It will be observed that when the slips are nearly unwound from the core 90 of the roll, they will be inclined from the roll 105 downwardly to the reduced opening of the channel support 86.

115 With this construction it is obvious that the number of strips wound upon the roll 14 may be varied and one or more of the lower strips may be turned inwardly within the register, 120 cut off and deposited within the register box 67; one or more sales slips may be discharged from the register; the length of the sales strips or tickets may be varied within wide limits, and the position of the shears, the 125 130

register box and the roller raising cam 39 may be varied accordingly; and the aligning mechanism is automatically actuated to insure that the several slips unwound from the roll 14 will be positively engaged and moved into register at the time they are positioned for receiving writing or printing thereon through the casing opening 17.

I claim:

1. In a register of the class described, means for feeding a plurality of perforated strips at each actuation of the register, an aligning mechanism comprising a finger movable to engage in the perforation of the strips and complete their feeding movement in alignment, said mechanism comprising means for pivotally mounting the fingers free from the strips to swing positively upwardly to engage in the perforations, rocking arms carrying said mounting means for completing the feeding movement of the fingers, and stop means for withdrawing the fingers from the perforations at the end of their aligning movement.
2. In an aligning mechanism for perforated strips in an account register, means for feeding strips a predetermined distance, aligning fingers having a pivoted shaft to swing them upwardly to engage the strip perforations at the end of the predetermined movement, means for moving the shaft and the fingers in engagement with strip perforations for aligning the strips, stop mechanism for withdrawing the fingers from the strip perforations at the end of the aligning movement of the fingers, means for preventing the upward movement of the aligning fingers in the returning direction, and resilient means for returning the aligning fingers to their original position.
3. In an aligning mechanism for a perforated strip account register, means for feeding a plurality of strips a predetermined portion of a complete movement, aligning fingers for engaging corresponding perforations of the strips, a rock shaft in which the fingers are mounted for upward and strip aligning movement, controlling means for the fingers for limiting the upward and aligning movement, a stop for withdrawing the fingers from engagement with the strips at the end of the aligning movement, a return carrier for preventing the upward movement of the fingers upon their return movement, and a spring for engaging the shaft to return the fingers in connection with said carrier after the fingers are withdrawn by the stop.

ADAM ROHNER.
